DESIGN FOR AN AUTOMOBILE BUMPER EXTENSION

Louis A. Koch, Jr., Louisville, Ky.

Application February 28, 1938, Serial No. 75,481

Term of patent 14 years

To all whom it may concern:

Be it known that I, Louis A. Koch, Jr., a citizen of the United States, residing near Louisville, in the county of Jefferson and State of Kentucky, have invented a new, original, and ornamental Design for an Automobile Bumper Extension, of which the following is a specification, reference being had to the accompanying drawing, forming part thereof.

I claim:

The ornamental design for an automobile bumper extension, substantially as shown.

LOUIS A. KOCH, JR.
